LOOSE-LEAF BINDER

Louis Supin, Brooklyn, N. Y., assignor to Boorum & Pease Company, Brooklyn, N. Y., a corporation of New York

Original application October 14, 1938, Serial No. 235,069. Divided and this application September 18, 1942, Serial No. 458,872

3 Claims. (Cl. 129—17)

The invention is particularly useful in binders of the kind usually known as shift type visible index prong binders, in which the sheets are filed with a top or bottom edge visible, i. e., in overlapping relation, and in which the sheets are moved to new positions by offsetting the prongs. This invention relates to novel improvements in means for locking the shifting mechanism in such loose leaf binders.

This application is a division of application Serial Number 235,069, filed October 14, 1938.

An object of the invention is to provide means whereby the prongs may be locked against inadvertent shifting. A further object is to prevent closing of the book when the prongs are offset.

The novel shift locking mechanism provides means to automatically lock the shifting mechanism as the book is closed so that even after the book is opened again, the shifting mechanism will stay locked until the operator purposely unlocks it.

The mechanism may further be used to prevent locking the shifting mechanism when it is in offset or shifted position, so that when the prongs are in offset position they can always be shifted back to normal position.

Other objects and advantages will appear more fully from the following description taken in connection with the accompanying drawing which forms a part of the specification in which:

Figure 1 is a composite plan view of the metal of a binder showing the novel locking means, the left hand end being shown in partially open unlocked but non-offset position, and the right hand end being shown in closed and locked position;

Figure 2 is a side view in elevation of one end of the metal of the binder of Fig. 1, parts being broken away to show details;

Fig. 3 is an end view of the binder of Figs. 1 and 2 with parts being shown in section.

In the embodiment shown, the binder consists of frame member or halves 50 and 51, having meeting faces or sides 52 and 53 respectively. Two sets of prongs 55 and 56 are rigidly borne by halves or boxes 50 and 51 respectively of the metal binding parts, which are hinged together in longitudinally sliding relation by a hinge pin 54. Hinge lugs 57 on the half 51 are of uniform length and are uniformly spaced while hinge lugs 58 on the other half 50 are shorter than the spaces between the lugs 57, and are spaced farther apart than the length of the lugs 57, as best shown in Figure 2, with the result that the halves are capable of longitudinal movement relative to each other upon the hinge pin 54.

The two halves, hinged together as above described, are provided with detents 59 slidably re-

tained by any suitable means on one half and cooperating with binder locking means on the other for holding the halves of the binder either in closed position, or in partially open or postion. One of these detents is shown at 59 as constituting a fin projecting through an elongated slot 62, in the face 52, the projecting part being shown as having two notches 600 and 601, and in Figure 3 the projecting part is shown as being arcuate, concentric with the pintle 54. The detent extends through a registering slot 99 in the opposite face 53. As shown in Figure 2 a bracket 73 is secured to the detent 59 on the under side of the half 50 and extends from the detent 59 to a gudgeon or sleeve 61 mounted on the hinge pintle 54.

The binder-locking means cooperating with the detent 59 comprises a locking catch or bar 60 which as shown in Figures 1 and 3 is mounted on the underside of the face 53 of the half 51 and there retained in longitudinally slidable relation by any suitable means. The bar 60 has a notch 100 shown in Figure 1. A tension spring 101 normally urges the bar 60 in a direction to project its extending end outward, which brings the notch 100 out of register with slot 99, so that the end of the notch engages with one of the notches in the detent 59 to hold the halves selectively in half open position when notch 600 is engaged, or closed position when notch 601 is engaged.

In order to insure cooperation between the locking means 60 which is on half 51, and the detents 59, which are slidably carried by half 50, and to insure register of the detents 59 with the slots 99, the gudgeons or lugs 61 associated with detents 59 are made approximately the same length as the space between lugs 57 on half 51, with the result that lugs 61 and detents 59 are relatively stationary, that is to say not longitudinally movable, with regard to the opposite side 51. In order to permit the sleeve 61 to fit in between adjacent lugs 57, the shorter lug 58 which would have occurred at this point is omitted or cut away. The slot 99 is longitudinally coextensive with the space between the adjacent lugs 57, so that the sleeve 61 therebetween retains the detent 59 which is bracketed thereto, at all times in register with the slot 99. The slot 62 in face 52 is longer than slot 99 in face 53, so that the left ends of the slots register when the parts are in normal non-shifted position as shown in Fig. 1, and the right ends register when the parts are shifted with the result that the detent 59 may enter slot 99 in face 53 and engage notch 100 in bar 60 in either shifted or non-shifted position.

If desired a spacer 78 may be provided on one of the meeting faces, and a slot of equal length may be carried by the other meeting face,

in such position that the two will register only when the halves are in normal non-offset position.

As illustrated, the novel means for locking the shifting mechanism comprise a shift locking bar or stop 641, assembled in the binder in such relation to the two halves 50 and 51 that it moves longitudinally with one of them but is relatively stationary longitudinally in relation to the other half; and a latch 650 which in closed position prevents longitudinal movement of bar 641, thereby preventing relative longitudinal movement between half 50 and prongs 55 on the one hand and half 51 and prongs 56 on the other.

The shift locking bar as illustrated has a finger 76 and a notch 690. The bar may be associated with strip 73 in any suitable way, as by spot welding, or it may be made unitary with detent 59 as in Fig. 6 of the application bearing Serial No. 235,-069. If desired, a guide 80 for the bar 641 may be provided.

The latch 650 is held upon web or top 66 of the half 50 by any suitable means. In the drawing it is shown pivoted to the underside of top 66 by a pin 81 and having a finger piece 670 projecting up through a slot in said top. The latch 650 is provided at one end with a tongue 680, and at the other end with another tongue or lug 82.

In operating the device, starting with the book in closed position, the halves 50 and 51 and the prongs 55, 56 will be in normal, non-offset position, and the meeting faces 52 and 53 will be adjacent each other as shown at the right end of Fig. 1. The latch will be closed and the tongue 82 of the latch 650 will lie in notch 690 of the shift locking bar 641, abutting finger 76 thereof, thus preventing shifting of the locking bar and of the prong bearing halves of the binder.

Pressure on the outwardly extending end of bar 60 will cause the bar to release notch 601 of fin 59 and will allow the two halves of the book to swing laterally open selectively either to fully open position where the fin 59 is entirely free of bar 60 or to the posting position shown in Figs. 1 and 3, where bar 60 catches notch 600 of the fin 59.

When the book has been opened and the meeting faces 52 and 53 have been moved laterally apart, the prongs will remain locked in normal position until the shift-locking mechanism is manually unlocked by pressure upon button 670 in the direction of the arrow R (see Fig. 1), moving latch 650 to the position shown in Fig. 1. In this position tongue 82 has left notch 690 and tongue 680 has passed through slot 70 in the face 52 of half 50 and protrudes between the meeting faces 52 and 53 of the two halves. The halves can now be shifted longitudinally so that the prongs 55 and 56 and the halves of the binder will then be in offset position. If half 50 be considered as moving, that half 50 and its lug 58 as shown in Fig. 2 will have moved toward the right along pin 54 until lug 58 abuts lug 57. The latch 650 will likewise necessarily have moved to the right. Shift lock 641 however will have remained in the position shown in Fig. 2, due to its rigid attachment to sleeve 61, which is held stationary between lugs 57 of the half 51.

In the longitudinally shifted, offset position finger 76 of the bar 641 will be in lateral alignment with the end 820 of tongue 82 of the latch 650.

The abutment of the finger 76 of the shift

locking bar against the end 820 of tongue 82 of the latch will prevent closing the latch 650 either by manual pressure upon button 670, or by pressure of face 53 against the end of tongue 680 as long as the parts are in offset position. This constitutes a safety factor, for it prevents accidental displacement of sheets through inadvertent closing of the book when the prongs are in offset position.

Before the book can be closed, the halves must be shifted longitudinally back to normal, non-offset position as shown at the left end of Fig. 1.

In this position, the latch 650 can be manually closed, if desired, by pressure upon the button 670 in the direction opposite to arrow R. Or in the alternative, by closing the book, thus bringing the faces 52 and 53 of the two halves together, the pressure of face 53 abutting against the end of tongue 680 will automatically close the latch.

From the foregoing description of the operation of the embodiment illustrated, the operation of modifications will be understood by those skilled in the art.

Other embodiments within the scope of the invention will occur to those skilled in the art.

I claim:

1. In a loose leaf binder, a pair of frame members each carrying a set of longitudinally spaced transversely extending prongs, means pivotally connecting said frame members to permit relative longitudinal sliding thereof to shift said prongs in combination with a shift locking stop member mounted underneath one of said frame members in relatively longitudinally slidable relation with respect thereto means movable with said stop member and engaging said pivotal connecting means and a latch pivotally mounted on said frame member and adapted to engage said shift locking stop member when said prongs are in non-shifted position to prevent shifting thereof while said latch is in engagement therewith.

2. In a loose leaf binder, a pair of frames each having a set of longitudinally spaced transversely extending prongs, said frames having depending flanges pivoted together for longitudinal shifting relative to each other, in combination with shift locking means comprising stop means for preventing said longitudinal shifting and a latch means pivoted on an axis parallel to the plane of and spaced from one of said flanges for movement alternately into latched position in engagement with said stop and alternately into unlatched position clear of said stop.

3. In a loose leaf binder, a pair of box members each comprising a top and a side, a set of longitudinally spaced transversely extending prongs secured in rigid relation to each box, means pivotally connecting said sides and permitting relative longitudinal sliding thereof to shift said prongs, in combination with shift locking means comprising a stop for preventing said longitudinal shifting and a latch moveable relative thereto alternately into latched position in engagement with said stop, and alternately into unlatched position clear of said stop, said stop being longitudinally slidably mounted inside one of the boxes on the side and below the top thereof, and said latch being pivoted to the underside of the same top and having a portion projecting through a slot in the same side, and having a finger piece projecting through a slot in said top.

LOUIS SUPIN.
